UNITED STATES PATENT OFFICE.

GEORGE C. HUNTER, OF CHICAGO, ILLINOIS.

HOIST.

SPECIFICATION forming part of Letters Patent No. 723,277, dated March 24, 1903.

Application filed November 22, 1902. Serial No. 132,374. (No model.)

To all whom it may concern:

Be it known that I, GEORGE C. HUNTER, a citizen of the United States of America, and a resident of Chicago, in the county of Cook 5 and State of Illinois, have invented certain new and useful Improvements in Hoists, of which the following is a specification.

The device in which I put my invention into practice is an improved form of hoist which 10 is particularly designed for use in an artificial-ice plant for lifting the cans of ice out of the refrigerating-tank. It will be understood, however, that my device may also be applied to other purposes.

15 The main objects of my invention are to provide an improved form of double cylindrical hoist adapted to be operated by fluid-pressure provided through either a gas or liquid medium and to provide an improved 20 form of valve connection between the two cylinders. I accomplish these objects by the construction shown in the accompanying drawings, in which—

Figure 1 is a longitudinal partly-sectional view of a hoist constructed according to my invention. Fig. 2 is an end view of same. Fig. 3 is a vertical section of the valve and valve-seat, taken on the line 3 3 of Fig. 1. Fig. 4 is a similar section taken on the line 4 4 of 25 Fig. 1. Fig. 5 is a front detail view of the valve-plate operating in connection with the valve-ports shown in Fig. 1, said ports being shown in dotted lines to illustrate the relative positions of the ports. Fig. 6 is a vertical section on the line 6 6 of Fig. 5. Fig. 7 is a horizontal section on the line 7 7 of Fig. 5.

In the device shown the cylinders 1 have therein the pistons 2, each having an outer arm 8, providing a bearing for the pulleys 9. 30 Said cylinders are connected at the middle part of the device by the casting 10, forming the valve-seat and being provided with the valve-ports 11, 12, 13, and 14. A middle passage 15 connects the two cylinders with the fluid-supply port 11 through a passage 16. The fluid-supply port 13 is connected with each cylinder at 17 through the passages 18 and 19. At the middle part of the device and depending from the casting 10 is an arm 20, 45 forming a bearing for the pulleys 21 and 22. A pair of extensions 23 are secured to the upper part of each cylinder 1, providing bear-

ings for the wheels 24. The wheels 24 may be mounted to run on a track 25, as shown in Fig. 2, thus supporting the hoist so that 55 same may be moved to different positions along the track. A cable 26 passes over the pulley 21, and thence over the forward pulley 9 at the right of Fig. 1, and continues over the forward pulley 9 at the left of Fig. 60 1, and thence passes around the other pulleys 9, of which one set is shown in Fig. 2, said cable continuing over the pulley 22 and engaging the eye 27 toward the right of the equalizing-bar 28. (Shown in Fig. 1.) The 65 bars 29 are of a common form used for lifting cans of ice in refrigerating plants.

The valve-plate 30 (shown in Figs. 3 to 7, inclusive) has the end 31 of its shaft seated in a suitable bearing in the casting forming 70 the valve-seat 10. The other end of said shaft has a handle 32 rigid thereon, whereby said valve-plate may be turned relatively of the valve-seat. The valve-plate 30 has an opening 33, communicating with the flexible fluid-inlet 34 through the chamber 35. Said valve-plate has on its inner face pockets 36 and 37, so arranged as to establish communication either between the ports 11 and 12 or between the ports 13 and 14. It will be 80 seen that when the valve-plate is turned so as to expose the port 11 to the opening 33 the pocket 37 will establish communication between the ports 13 and 14. When the valve-plate is turned so as to expose the port 13 to 85 the opening 33, then communication between the ports 11 and 12 will be established through the pocket 36. The ports 12 and 14 are exhaust-ports communicating with the outer atmosphere. 90

The operation of the device shown is as follows: When the air or fluid is forced through the flexible connection 34 and port 11 into the passage 15, the fluid will act against the inner ends of the pistons 2, forcing said pistons outwardly, and thus carrying the pulleys 9 outwardly, so as to take up the cable 26, and thus raise the equalizing-bar 28, with such weight as may be attached thereto. The valve-plate 30 should at this time have 100 the opening 33 opposite the port 11. The fluid in the outer end of each cylinder will now be forced through the connections 19, the passage 18, the port 13, the pocket 37,

and thence through the port 14 to the outer atmosphere. When it is desired to lower the equalizing-bar 28 and the weight carried thereby, the operator will, by means of the handle 32, turn the valve-plate 30 so as to expose the port 13 to the opening 33. The fluid will now be forced into the cylinders at 17, where it will exert pressure to return the pistons toward the position in which they are shown in Fig. 1. The fluid at the inner faces of the pistons will now be forced through the passage 15, the port 11, the pocket 36, and the port 12 to the outer atmosphere. When the valve-plate is in the relative position shown in Fig. 5, the ports 11 and 13 will both be closed and neither of same will be in communication with the exhaust-ports 12 and 14.

It will be understood that some of the details of the construction shown may be altered without departing from the spirit of my invention. I therefore do not confine myself to such details, except as hereinafter limited in the claims.

What I claim as my invention, and desire to secure by Letters Patent, is—

1. The combination of a pair of connected cylinders; a pair of oppositely-acting pistons, each carrying a pulley at its outer end; a fluid-supply chamber; a valve communicating with both the inner and outer ends of said cylinders, and adapted to exhaust the fluid at the outer ends of said cylinders and at the same time admit fluid into their inner ends, and to exhaust the fluid from the inner ends of

35 said cylinders and at the same time admit fluid into their outer ends; and a cable passing over said pulleys and adapted to be taken up through the outward movement of said pistons, substantially as described.

40 2. The combination of a pair of connected cylinders; a pair of oppositely-acting pistons, each carrying a pulley at its outer end; a fluid-supply chamber; a valve-seat between said cylinders having a pair of fluid-supply ports, one of said supply-ports communicating with the inner ends of both of said cylinders, and the other communicating with the outer ends of both of said cylinders; a pair of exhaust-ports; a valve-plate adapted to

50 shut off the fluid-supply chamber from either or both of said fluid-supply ports, said valve-plate having an opening adapted to connect

either of the supply-ports with the fluid-supply chamber, and having a pair of pockets

55 each adapted to establish communication between one of said supply-ports and one of said exhaust-ports, and suitably arranged so that when one of said supply-ports is in communication with the fluid-supply chamber, the

60 other of said supply-ports will be in communication with its respective exhaust-port; and a cable passing over said pulleys, and adapted

65 to be taken up through the outward movement of said pistons, substantially as described.

3. The combination of a pair of connected cylinders; a pair of oppositely-acting pistons;

a fluid-supply chamber; a valve communicating with both the inner and outer ends of said cylinders, and adapted to exhaust the fluid at the outer ends of said cylinders, and at the same time admit fluid into their inner ends, and to exhaust the fluid from the inner ends of said cylinders and at the same time admit fluid into their outer ends, substantially as described.

4. The combination of a pair of connected cylinders; a pair of oppositely-acting pistons; a fluid-supply chamber; a valve-seat between said cylinders having a pair of fluid-supply ports, one of said supply-ports communicating with the inner ends of both of said cylinders, and the other communicating with the outer ends of both of said cylinders; a pair of exhaust-ports; a valve-plate adapted to 80 shut off the fluid-supply chamber from either or both of said fluid-supply ports, said valve-plate having an opening adapted to connect either of the supply-ports with the fluid-supply chamber, and having a pair of pockets 85 each adapted to establish communication between one of said supply-ports and one of said exhaust-ports, and suitably arranged so that when one of said supply-ports is in communication with the fluid-supply chamber, 90 the other of said supply-ports will be in communication with its respective exhaust-port, substantially as described.

5. The combination of a pair of oppositely-disposed connected cylinders provided with 100 a hanger adapted to support same in a substantially horizontal position; a pair of oppositely-acting pistons, each carrying a pulley at its outer end; a fluid-supply chamber; a valve adapted to establish communication 105 between said fluid-supply chamber and the inner ends of said cylinders or between said fluid-supply chamber and the outer ends of said cylinders, and being adapted to exhaust the fluid at the outer ends of said cylinders 110 when such communication is established with their inner ends, and to exhaust the fluid-supply from the inner ends of said cylinders when said communication is established with their outer ends; and a cable passing over 115 both of said pulleys and having a depending port adapted to be taken up through the outward movement of said pistons, substantially as described.

6. The combination of a pair of connected 120 cylinders; a pair of oppositely-acting pistons; a fluid-supply chamber; the connection between said cylinders providing a valve-seat adapted to support a rotary valve-plate, said valve-seat having a pair of fluid-supply ports 125 and a pair of exhaust-ports; one of said supply-ports communicating with the inner ends of both of said cylinders and the other communicating with the outer ends of both of said cylinders; a valve-plate journaled in said valve-seat and adapted to shut off the fluid-supply chamber from either or both of said supply-ports, having an opening adapted to connect either of said supply-ports with the fluid-sup-

ply chamber, and having a pair of pockets each adapted to establish communication between one of said supply-ports and one of said exhaust-ports, and suitably arranged so that when one of said supply-ports is in communication with the fluid-supply chamber, the other of said supply-ports will be in communication with its respective exhaust-port, substantially as described.

5 7. In a hoist, the combination of a portably-suspended frame; a pair of oppositely-movable members, each having a pulley at its outer end; a pair of pulleys journaled on said frame independently of said movable members; and a cable passing over both pulleys on said movable members and having each of its ends passing over one of the other pulleys and depending therefrom in suitable manner to have said ends raised through the 15 outward movement of said movable members; and means for simultaneously moving said members in opposite directions relatively of said frame, substantially as described.

8. In a hoist, the combination of a portably-suspended frame; a pair of oppositely-movable members on said frame, each movable relatively of said frame, toward and away from each other, and each having a pulley at one end; a cable passing over both of said

pulleys and having its ends depending from 30 said frame and adapted to be raised through the opposite movement of said members; and means for simultaneously moving said members in opposite directions relatively of said frame, substantially as described.

9. In a hoist, the combination of a frame; a pair of oppositely-movable members on said frame, each movable relatively of said frame, toward and away from each other, and each having a pulley at one end; a pair of pulleys 40 journaled on said frame independently of said movable members; a cable passing over both pulleys on said movable members and having each of its ends passing over one of the other pulleys and depending therefrom 45 in suitable manner to have said ends raised through the opposite movement of said movable members; and means for simultaneously moving said members in opposite directions relatively of said frame, substantially as de- 50 scribed.

Signed at Chicago this 17th day of November, 1902.

GEORGE C. HUNTER.
